UNITED STATES PATENT OFFICE.

EWALD WALTHER, OF DURLACH, BADEN, GERMANY.

PRESS FOR THE COLD EXTRUDING OF TUBES FROM METAL DISKS.

Application filed January 15, 1927, Serial No. 161,454, and in Germany March 12, 1925.

This invention relates to a press designed for the cold-extruding of tubes from a metal disk by means of a pressing plunger and a mandrel, as well as a matrix, in which a disk 5 that arrives automatically in front of the aperture of the matrix is perforated by the mandrel and then subjected to the pressure of said plunger in such a manner that the tube-forming material is pressed out between 10 the outer wall of the plunger and the inner wall of the matrix, counter to the feed movement of the mandrel, over and along the outer wall of the plunger, there being formed simultaneously therewith a hollow 15 neck which is threaded later on.

The gist of the invention resides in the first place in the fact that the mandrel which is guided in the plunger is withdrawn by a suitable mechanism as soon as both members, 20 together with the tube, have left the matrix, whereby the new effect is attained that air can pass into the interior of the tube prior to its being stripped off from the plunger so that a vacuum which would entail de- 25 struction of the tube at the high speed of the extruding procedure (50-60 revolutions of the machine in a minute) cannot arise.

The invention is illustrated diagrammatically and by way of example on the accompanying drawings on which Figure 1 is 30 partly a side-view of, and partly an axial section through, the mechanism, the plunger being in its operative position; Figures 2 and 3 show the same members as in Fig. 1 in other positions, the frame also shown in Fig. 1 being omitted in these figures (2 and 3); Figure 4 shows in plan and in side-view one of the metal disks used for the manu- 35 facture of the tubes; Figure 5 is a cross-section in the plane 5-5 of Fig. 1, seen from the left to the right, and shows the conveying means for the tubes made; Figure 6 is a vertical longitudinal section through the matrix, the mandrel, the plunger, and a sprayed tube, these parts, except the matrix, being broken off at their left-hand ends; Figure 7 shows the same parts as in Fig. 6 in such other position that air can enter into the tube, and Figure 8 is a view similar to Fig. 3, but shows a modification.

The details of the press are as follows:

A (Figs. 1-3) denotes the main shaft, to which is secured a disk provided with a lateral pin s' bearing a connecting rod K 55 connected at k' with the members e and e' of a toggle-joint lever. The member e is

hinged at e^2 to the frame B of the press, and the member e' is connected by a cross-pin e^3 with a sliding member i located in another sliding member h carried by a pair 60 of guide ledges h^2 .

k (Figs. 6 and 7) denotes the mandrel, and l the plunger; the former is affixed in the sliding member i (Figs. 1-3) and the other in the sliding member h . The free 65 end of the plunger is of conical shape, as shown at l' in Figs. 6 and 7.

The lever member e' is provided with a downwardly directed lug o extending through recesses o' of the sliding members 70 i and h . The lug o contacts with a roll p carried by the sliding member h . This roll engages a cavity o^2 of said lug when these parts are in the position shown in Fig. 2.

The matrix b is located in the frame B of 75 the press; its shape appears from Figs. 6 and 7. Just in front of the same terminates a guide channel a (Fig. 1) through which are supplied the metal disks c (Fig. 4) serving for the manufacture of the tubes. q 80 denotes a stripping member formed by a centrally perforated disk. n is a bell-crank lever fulcrumed on the pivot n' and contacting at its upper end with a downwardly directed projection h' of the sliding member 85 h , and at its lower end with a cam m by which it is oscillated when the shaft A is rotated. Between the end of the supply channel a and the stripping member q , but below these parts, is located an endless 90 conveying band r (Figs. 1, 3 and 5) by which the tubes g made in the press are carried away.

The manner of operation of the press is as follows:

In the position of the parts in Fig. 1 the toggle-joint lever e e' is stretched and the two sliding members are, therefore, in their utmost position to the right, which is true, of course, also of the mandrel k and the die 100 l , their position relatively to the matrix being now that shown in Figs. 1 and 6. Prior thereto, that is to say, before the plunger and the mandrel had been moved to the right (without any movement relatively to 105 each other), a metal disk c (Fig. 1) had been placed in front of the matrix, i. e. between it and said tools k and l and centered by suitable means, and when then these tools are shoved to the right, into the position 110 shown in Figs. 1 and 6, the disk is pierced by the pointed end of the mandrel k and a

tubular portion g' is formed around the hole, that tubular portion forming afterwards the neck of the tube made in the press and being then provided with an exterior thread for the reception of the closing cap. The matrix b is, of course, shaped accordingly.

The shaft rotates in the direction indicated by the arrows in Figs. 1-3, and when it has performed a part rotation of about 60 degrees (from the position Fig. 1) it commences to lift the toggle-joint lever members $e e'$ whereby the two sliding bodies h and i are withdrawn from the matrix, together with the formed tube portion upon them. When the angular motion of the shaft mounts to nearly ninety degrees, the position of the lug o relatively to the roll p is such that, this latter can engage the cavity o^2 whereby the sliding body i is shifted a little relatively to the sliding body h , as is, consequently, also the mandrel relatively to the die, as shown in Figs. 2 and 7. The pointed end of the mandrel has now left the neck g' , and air can enter into the tube. The bell-crank lever n has not yet been moved because its lower arm has not yet been actuated by the cam m .

The rotation of the shaft A is continued and the toggle-joint lever $e e'$ lifted by and by into the position shown in Fig. 3, in consequence whereof the lug o is so much lifted that its cavity o^2 leaves the roll p whereby another movement of the two sliding bodies relatively to each other is caused, their position with respect to one another being now the same as in Fig. 1, but both sliding bodies having finally arrived in their utmost left-hand position.

While the sliding bodies h and i have covered the way from the right to the left, also the tools k and l have covered the same way and the plunger 1 has completely left the stripping member g . The diameter of the central hole of this member is a little smaller than the outer diameter of the tube, and the tube is, therefore, stripped off the plunger when this latter is moved from the right to the left, as described. The stripped-off tube g falls upon the conveying band r by which the tubes are conveyed to another working place or machine where the tubes are further treated and finished.

Instead of a stationary stripper, as g , a movable one or, more precisely, a bipartite movable stripper, such as $g' g'$ (Fig. 7), may be used.

In the modification shown in Fig. 8, in which the position of the toggle-joint lever and of the members h and i is the same as in Fig. 3, the movements of these latter members relatively to each other are effected by means of another, smaller toggle-joint lever y jointed at one end to the member i and at the other end to a cross-wall of the

member h . The toggle-joint lever y is connected by a rod v with one arm of a three-armed lever u fulcrumed on the bolt z ; the other two arms of this lever are rocked by cams w and x . When the crank shaft $S S'$ is rotated in the direction indicated by the arrow in Fig. 8, the toggle-joint lever $e e'$ will be stretched practically in the same manner as in Fig. 1 after the crank shaft $S S'$ has made one half of one revolution, the guide bodies being thereby moved into their pressing position. The small toggle-lever y which actuates the mandrel and is moved by the rod v , the three-armed lever u , and the cams w and x , remains stretched while the other toggle-lever ($e e'$) is being stretched as just described.

When the tube has been extruded, as in Figs. 1 and 6 and been withdrawn from the matrix b by the rearwardly moving guide bodies i and h , or by the tools l and k respectively, the toggle-joint lever y will be bent through upwardly by the parts $w' x'$ of the cams w and x , the lever u , and the rod v , whereby the mandrel k is withdrawn so much that, just as in Figs. 2 and 7, atmospheric air can enter between the outer edge of the die $l l'$ and the inner wall of the tube $g' g'$ so that the tube can be stripped off quickly and automatically without any damage to it. According to the length of the cam portions w' and x' the mandrel k remains withdrawn for a shorter or longer time, and can then be brought anew into its pressing position at any desired or required time.

I claim:

1. A press for the cold extruding of tubes from a metal disk comprising in combination a stationary matrix having a cavity shaped according to the head and neck of the tubes to be formed, and adapted to extrude rearwardly the surplus tube forming material; a plunger shaped according to the tube body and serving as a carrier for the extruded tube material; a mandrel extending throughout said plunger and having a pointed free end adapted to form an opening through the neck and head of the tube; means to shift the plunger and mandrel, said means adapted at first to introduce the plunger and mandrel into the matrix, then to withdraw the same with the tube from said matrix, whereupon said means will set the plunger at rest and withdraw further the mandrel whereby to permit air to enter into the tube, said means finally withdrawing again the plunger and mandrel; a stripping member riding over the mandrel; and means for conveying away the finished tubes.

2. A press for the cold extruding of tubes from a metal disk comprising in combination a stationary matrix having a cavity shaped according to the head and neck of the tube to be formed, and adapted to ex-

trude rearwardly the surplus tube forming material; a plunger shaped according to the tube body, and serving as a carrier for the extruded tube material; a mandrel extending throughout said plunger and having a pointed free end adapted to form an opening through the neck and head of the tube; a pair of sliding members mounted one within the other, one of said members being connected to the plunger, and the remaining member being connected to the mandrel; a motion transmitting mechanism including a cam and levers jointed to said sliding members, said mechanism adapted at first to in-

15 troduce the plunger and mandrel into the matrix, then to withdraw the same with the tube from said matrix, whereupon said mechanism will set the plunger at rest and withdraw further the mandrel, whereby to permit air to enter into the tube, said mechanism finally withdrawing again the plunger and mandrel; a stripping member riding over the mandrel; and conveying means for taking away the finished tubes.

20 In witness whereof I have hereunto set my hand.

EWALD WALTHER.
